Primary Examiner — Shawn T Gingrich*Assistant Examiner* — Angela C. Ligon(74) *Attorney, Agent, or Firm* — Hoffman Warnick LLC(57) **CLAIM**

The ornamental design for an apparatus for electric vehicle charging, as shown and described.

DESCRIPTION

FIG. 1 is a front view of an apparatus for electric vehicle charging showing the new design;

FIG. 2 is a rear view thereof; and

FIG. 3 is a left view thereof;

FIG. 4 is a right view thereof;

FIG. 5 is a top view thereof;

FIG. 6 is a bottom view thereof; and,

FIG. 7 is a perspective view thereof.

The dash-dash broken lines in FIGS. 1-7 depict portions of the apparatus for electric vehicle charging that form no part of the claimed design.

1 Claim, 7 Drawing Sheets(56)
